APPARATUS FOR TREATING MATERIAL ON
PROPELLER BLADESJohn O. Antonson, Akron, Ohio, assignor to The
B. F. Goodrich Company, New York, N. Y., a
corporation of New York

Application October 17, 1942, Serial No. 462,372

2 Claims. (Cl. 154—41)

1

This invention relates to the treating of material on elongated structures, and especially to the adhering of protective strips of rubber-like material to the leading edges of airplane propeller blades.

Protective strips of rubber or other rubber-like material are often desirable on the leading edge of aircraft propeller blades to protect the blade from abrasive contacts, and to conduct anti-freeze liquid along the leading edge of the blade by means of conduits or grooves in such strips to prevent the accumulation of ice on the blade.

Heretofore, in attempts to provide for adhering such strips to the smooth surfaces of blades by means of an air-curing adhesive of rubber or other rubber-like material, difficulty has been encountered in providing for sufficient adhesion between the rubber-like material of the strip and the blade to withstand the effects of air-flow over the blade, centrifugal forces, vibrations of the blade, and other forces encountered in operation of the airplane especially in the presence of severe abrasion. The problem of providing for successful adhesion under these conditions has been complicated by the sharpness of the leading edge contours over which the strip is to be conformed and secured. Also, an objectionable delay has been necessary after application of such adhesives to permit drying or curing at normal air temperatures and under only the slight pressure of the weight of the protective strip. The difficulties of the problem are complicated by the fact that the expedient of roughening the smooth surface of a blade may have undesirable effects on the blade structure.

The chief objects of the present invention are to provide means for effectively adhering a strip to the narrow, curved edge or side of the structure; to provide means for adhering a protective shoe to the leading edge of an aircraft propeller blade in a manner to prevent separation between the shoe and the blade under the forces encountered in use, and to provide apparatus for applying a combination of heat and pressure at the leading edge of a propeller blade to a protective strip of rubber-like material placed thereon to effect attachment between the protective strip and the blade by vulcanization.

Further objects are to provide portability of the apparatus and attachability to a blade in the field and while the blade is on an airplane; to provide apparatus adapted for use interchangeably on variously shaped edge contours; to provide means incorporated in such apparatus for

2

forming configurations on the protective strips while adhering the strips to a blade; to provide for durability of structure, and to provide for economy and convenience of manufacture and use.

These and further objects will be apparent from the following description, reference being had to the accompanying drawing in which:

Fig. 1 is a perspective view of a portion of an airplane propeller and hub assembly having apparatus constructed in accordance with and embodying the invention mounted on a blade thereof, parts being broken away and sectioned for illustration.

Fig. 2 is a perspective view, partly broken away and sectioned, of a portion of the apparatus of Fig. 1, but on an enlarged scale.

Fig. 3 is a view like Fig. 2, but of a modified construction.

Fig. 4 is a view like Fig. 2, but of a further modified construction.

Figs. 5 and 6 are views in cross-section of matrices which may be used in the apparatus.

In the illustrative embodiment of Figs. 1 and 2 of the drawing, apparatus for applying heat and pressure to a protective strip of rubber or other rubber-like material on the leading edge of a propeller blade, to attach the strip to the blade effectively by adhesion or vulcanized bond, is indicated generally at 10. The apparatus 10 is shown mounted on a blade 11 of a propeller at the nose of a fuselage or of a motor nacelle of an aircraft, a portion of which is indicated generally at 12 in Fig. 1.

The apparatus 10 of this embodiment comprises a heating element 13 of generally U-shape cross-section, as shown, which includes a body 14 of yieldable insulating material such for example as rubber or other rubber-like material, compounded for insulation adapted to overlie uniformly a protective strip 15 on the leading edge of the propeller blade 11 to transfer heat from the element 13 to adhesive material 17 disposed between the protective strip 15 and the blade 11.

Heat is supplied to the element 13 preferably by a plurality of resistance wires 16, 16 embedded in the body 14 of insulating material. A larger number of wires, or wires of greater heating effect, is desirable at sections of the blade and material of relatively greater thickness than at sections of relatively less thickness to provide for uniform penetration and application of heat at all portions of the protective strip. Alternatively, the heating element 13 may comprise electrically conductive material, such for exam-

ple as rubber or synthetic rubber or other rubber-like material compounded with graphite, acetylene black, or other suitable electrically conductive material. Lead wires 16a, 16a supply a connection between the heating unit and any suitable source of electricity.

Pressure is applied to the protective strip 15 preferably by means of an inflatable element 18 of generally V-shape cross-section, as shown, adapted to overlie and press against the heating element 13. The inflatable element 18 preferably comprises a hollow body of a suitable yieldable material such for example as rubber or other rubber-like material with or without fabric reinforcement and may be expansible or substantially inexpansile, as desired. Air or other pressure fluid may be supplied to the inflatable element 18 as by means of a valve stem 19, shown in Fig. 1.

The inflatable bag 18 is restrained at its outward sides as by means of a non-stretchable insulating covering 20 of square-woven fabric or other suitable material for holding the heating element 13 and the inflatable element 18 on the blade 11, during the application of heat and pressure.

The covering 20, the inflatable bag 18, the heating element 13 and the pad 14 are preferably assembled on a form of the general shape of the propeller blade or other elongated structure on which the apparatus is to be used so that the pad 14 may be cured in the general shape of the edge of blades of its intended use. The parts of the apparatus 10 are preferably cured or otherwise suitably attached together to provide a unitary structure for convenience of handling in use.

The apparatus 10 may be mounted on a blade by sliding the uninflated apparatus over the tip of the blade 11, enlargement of the space in the bag as a result of deflation making this feasible, or by the provision of a divided construction together with suitable fasteners, such for example as a slide fastener attachment 21, or by other suitable attaching means.

The insulating material of the heating element may, if desired, be of a relatively stiff construction, if desired, so that the element will conform substantially to the edge contours of a blade, independently of the pressure applied by the inflatable bag, because of the stiffness of the element.

In the embodiment of Fig. 3, the apparatus comprises a stiff or rigid metal member 22 of arcuate section enclosing an expansible bag 23 in a manner to restrain expansion of the bag 23 in the outward direction and to confine such expansion to the inward direction toward the contours of the leading edge of a blade 24 to press against a protective strip 25 disposed along such edge to effect adhesion of the strip 25 to the blade 24.

The expansible bag 23 of this embodiment permits use of the apparatus interchangeably on various shapes of blades and other elongated structure. A suitable heating element 26 is incorporated in the inward surface of the bag 23 to apply heat to the structure for the attachment of the strip 25 to the blade 24, together with the pressing force of the expansible bag 23. The heating element 26 may be attached to or molded integral with the bag 23 and may comprise wires 27, 27 embedded in a body 28 of flexible material adapted to conform to various contours of blade edge or elongated structure, or the ele-

ment may comprise other suitable electrically conductive material, as hereinabove described.

The bag 23 is preferably of such dimensions as to extend beyond the ends of the strip 25 to insure an adequate supply of heat at the ends of the strip 25 and to extend beyond the side margins to provide a tendency for movement of the inner pressing surface of the bag 23 laterally of the strip 25 to provide a wiping action of the bag 23 on the strip 25.

The apparatus of Fig. 3 may be secured to the blade 24 by any suitable means, as for example by means of one or more straps 29 encircling the apparatus at suitable positions along the blade 24 and secured to projecting flange portions 30 of the arcuate member 22 to secure the apparatus on the blade 24.

In the embodiment of Fig. 4, fins 31, 31 of metal or other suitable heat and pressure resistant material are incorporated in a heating element 32 in a manner to form grooves in a protective strip 34 for conducting anti-freeze liquid along the leading edge of a blade. The fins 31, 31 may be partially embedded in yieldable material 25 of the element 32 with a sufficient height of fin projecting therefrom to form grooves of the desired depth in the strip 34 under heat and pressure applied by the apparatus 33. If desired the fins 31, 31 may be provided with flanges, dovetails or other locking portions for further anchorage in the material of the element 32.

If raised ribs are desired on the strip 34 for conducting such liquid, suitable corresponding depressions may be provided in the inside surface of heating element 32 to form such ribs. Alternatively, a stiff insert, such for example as the insert 35 shown in Fig. 5 may be used at the inner face of the heating element 32 and this insert may be provided with suitable depressions 36, 36 adapted to form ribs in the material of the strip 34 under heat and pressure. An insert 37 of suitable shape-retaining material may be provided between the heating element and the protective strip to form grooves in the strip by means of raised portions 38, 38 provided on the insert 37, and may be in the form shown by way of example in Fig. 6. The heating element 32 may comprise heating wires 39a and an outer layer of insulating material 39, and pressure may be obtained from an inflatable member 40 within the retaining cover 33.

Apparatus of the invention provides for great strength of adhesion or bonding through heat and pressure, and makes possible rapid and convenient installations on an airplane propeller blade in the field, without necessitating the removal of the blade from the airplane.

Variations may be made without departing from the scope of the invention as it is defined by the following claims.

I claim:

1. Apparatus for treating material on the leading edge of a propeller blade, said apparatus comprising an inflatable flexible walled element generally U-shape in cross section for confining said material between said inflatable element and said leading edge, a heating element generally U-shape in cross-section secured to said inflatable element and located at the inner face of the U-shape inflatable element for positioning adjacent said material, cover means secured to said U-shape inflatable element and extending from the latter element and providing with said latter element a tubular open-ended body adapted to be mounted over the propeller blade entirely around the same,

and means for inflating said U-shape inflatable element to tension said tubular body about said blade while pressing said heating element toward said material.

2. Portable apparatus for treating material on the leading edge of a propeller blade, said apparatus comprising an inflatable flexible walled element generally U-shape in cross-section for confining said material between said element and said leading edge, an electrical heating element generally U-shape in cross-section secured to said inflatable element and located at the inner face

of the U-shape inflatable element for positioning against said material, cover means secured to said U-shape inflatable element and extending from the latter element and providing with said latter element a tubular open-ended body adapted to be mounted over the propeller blade entirely around the same, and means for inflating said U-shape inflatable element to tension said tubular body about said blade while pressing said heating element against said material.

JOHN O. ANTONSON.
